MEANS AND METHOD OF STAPLING
BOX PARTS

Guilford C. Babcock, Jr., Summit, N. J., assignor
to Stapling Machines Co., a corporation of
Delaware

Application December 11, 1934, Serial No. 756,942

8 Claims. (Cl. 1—8.3)

This invention relates to a means and method of clinching the ends of staples which are driven through box or crate sides, and particularly to clincher blocks used for clinching staples in the manufacture of wirebound boxes.

It is an object of the invention to provide a clincher block which will control the direction in which the staple leg clinches.

It is a further object of the invention to control the clinching direction of the staple legs so as to cause them to lie across the grain of the wood when a wooden box side is used.

It is another object of the invention to provide a clinching means to control the radius of the clinching curve.

It is a further object to provide a clinching means which will control the amount or thickness of wire which is allowed to lie below the surface of the box material after clinching.

It is a further object to provide a clinching means which will efficiently clinch the staple legs in the box material without unduly rupturing or weakening the material.

It is a further object to provide a clinching means which will so clinch the staple legs in the box side as to increase the holding power of the staple.

It is a further object to provide a clinching means which will bury the sharp staple points in the box material.

It is a further object to provide a clincher block for a stapling machine which will reduce the load on the machine when clinching and the consequent wear on the parts thereof.

It is a further object to provide a clinching means which will permit the use of thinner side material in the manufacture of wirebound boxes and crates.

Other objects will be in part obvious and in part pointed out hereinafter.

One illustrative embodiment of the invention is shown in the accompany drawings, in which:—

Figure 1 is a perspective view of a clincher block embodying the invention.

Fig. 2 is a perspective view of a sectional portion of the clincher block.

Fig. 3 is a perspective view of the clincher block showing the relative position of the block and a staple at the start of a clinching operation.

Fig. 4 is a perspective view of one type of wirebound box blank.

Fig. 5 is an enlarged perspective view partly in section of a portion of the box blank and showing the manner in which a staple is driven

over a binding wire through an exterior batten or cleat and through the sheet of side material and is clinched on the under side of the side material.

Fig. 6 is an enlarged perspective view partly in section of another portion of the box blank and showing the manner in which a staple is driven over a binding wire and through a sheet of side material and is clinched on the under side of the side material.

Fig. 7 is an enlarged top plan view of a portion of the box blank and illustrating the manner in which the staple legs are clinched in opposite directions parallel to the binding wire and across the grain of the wood.

Figs. 8, 9, and 10 are enlarged perspective views of a portion of the blank showing the manner in which the staple leg is driven over the binding wire through the box materials and is clinched on the underside of the box materials.

Figs. 11, 12, and 13 are similar views, but showing the manner in which a staple leg which has been deflected from its normal course of travel by the box materials is clinched on the under side of the material.

Referring to Fig. 4, the type of wirebound box blank there shown consists of four sections of side material 1, preferably of rotary cut veneer or resawed lumber, each section being provided at one end with an interior cleat 2, and at the other end with an exterior cleat 3. The several sections are connected together in foldable relationship by binding wires 4 stapled thereto.

The materials entering into the box blank are usually positioned on endless conveyor chains and moved beneath staple forming and driving mechanism which forms staples and drives the staples over the binding wires and through the box materials and clinches the staple legs on the under side of the box materials.

As shown in Fig. 7, the binding wires 4 are stapled to the side material 1 across the grain of the side material and preferably at substantially a right angle to the grain of the side material.

The staples designated 5 straddle the binding wire 4 at an angle to cause the staple legs to enter the side material at spaced points across the grain of the side material to avoid possible splitting of the side material which might follow the driving of both staple legs in a line parallel with the grain of the side material.

To further avoid splitting and rupturing of the side material and to increase the holding power of the staple, the clincher block of this invention causes the staple legs to clinch in

opposite directions and across the grain of the wood, as shown in Fig. 7, and also causes each staple leg after it emerges from the under side of the box material to curl in such a way that 5 the point of the staple leg will enter the under side of the box material at a point relatively remote across the grain from the point at which the staple leg emerged from the side material, as shown in Figs. 5 and 6, all with the result 10 that the staple is securely clinched to the side material without splitting or unduly rupturing the same.

The curling of the staple leg in the manner hereinafter described prevents the staple leg 15 from crushing and weakening the fibers of the side material and increases the holding power 20 of the staple. As shown in Fig. 5, the staple emerges through the side material 1 at the point "X", and the point of the staple reenters the side material at the point "Y", and the portion 25 of the curled staple leg between the points "X" and "Y" lies almost wholly beneath the side material 1, instead of being imbedded therein, as in prior clinching practices.

30 The advantages of driving and clinching the staple in the manner hereinbefore pointed out is best illustrated in Fig. 7 by reference to the lines there shown and marked "A", "B", "C" and "D". When the staple is driven over the binding wire 4, the legs enter and pierce the side material 1 along the lines "A" and "B", i. e., at 35 separated points across the grain of the wood, and when the legs of the staple are curled in opposite directions their points enter the side material respectively along the lines "C" and "D", i. e., at two points differently spaced across the grain of the side material. Thus, there is no possibility of any staple piercing the side material at two points parallel to the grain of the 40 wood. Such a stapling and clinching permits the use of thinner side material.

45 Heretofore staple legs have been usually clinched by imbedding the legs in the wood. Such a clinching compresses and ruptures the fibers of the wood where the leg is imbedded in 50 the wood, thus weakening the wood at that point. For example, if the wood is $\frac{1}{8}$ " (.125") thick, and the staple wire is eighteen gauge or .047" in diameter, and the staple wire is imbedded in 55 the wood to the extent of the diameter of the wire, .047" of the wood will be ruptured, leaving intact only .078" (.125" minus .047" equals .078") or 62½% of the wood. When the staple is stiff enough to resist unbending, it will under 60 stress break through the thin portion of the wood remaining intact. An imbedded clinch, therefore, in the example given, reduces the holding power of the wood 37½%. The percentage of loss of holding power is greater in thinner woods.

65 The clincher block which causes and controls the clinching in the manner hereinbefore described is shown in Fig. 1. It consists of a metal block preferably of steel and of oblong shape in horizontal cross-section, as there shown. Running diagonally across the upper surface of the block is a ridge 8 located in substantially the same horizontal plane as the upper surfaces 9 and 9' of the ends of the block. Extending from one side of the ridge 8 are a series of 70 parallel grooves 10, and extending from the other side of the ridge 8 are a series of similar parallel grooves 10'. The grooves 10 and the grooves 10' are parallel to each other and parallel to the longitudinal center line of the block.

75 The block is positioned beneath the materials to be operated upon so that the binding wire will lie parallel with the grooves 10 and 10', and the grain of the side material 1 will lie at right angles to the grooves 10 and 10', so that when a staple 5 is driven at an angle over the binding wire and at an angle to the ridge 8, as shown in Fig. 3, one leg of the staple will enter one of the grooves 10 on one side of the ridge 8, and the other leg will enter one of the grooves 10' on the other side of the ridge 8 and be curled in the manner presently described. If the staple legs in passing through the material are not deflected by the material they will usually enter the grooves 10 and 10' as shown in Fig. 3. If, however, the legs of the staple are deflected as frequently occurs, the legs may enter one or the other of the grooves 10 and 10', as pointed out hereinafter, and for that reason the block is provided with a plurality of grooves (five in the 20 illustrative embodiment) on each side of the ridge 8, so that no matter what the extent of the deflection of the staple legs may be, they will nevertheless each enter one of the grooves provided to receive them.

25 As best shown in Figs. 8, 9 and 10, the grooves curve downwardly from the ridge 8 to cause the point of the staple to curl when it strikes the bottom of the groove, as shown in Fig. 9. Continued driving of the staple causes its point to 30 curl upward and enter the under side of the material, as shown in Fig. 10. The depth of the groove is substantially equal to the diameter of the staple wire, so that when the clinching operation is completed the portion of the staple leg 35 marked "Z" in Fig. 10 will lie below the under surface of the side material instead of being imbedded in the side material.

40 The curvature of the groove is such as to accommodate itself to deflection in the staple legs during their passage through the material. Normally the staple emerges from the side material at the point "P" in Fig. 8, and is curled in the manner shown in Figs. 9 and 10. Occasionally, however, the staple leg is deflected in 45 its passage through the material and emerges at the point "P'" in Fig. 11. When the staple leg is pushed against the hard surface of the groove (being confined and guided as it is close to the point of contact) the leg will curl on a radius 50 the size of which is governed by the angle between the leg and the surface it contacts with. Hence in the clincher block of this construction, the above-mentioned radius is very accurately controlled under all circumstances by the use of 55 the curved or arcuate groove. The angle "E" in Fig. 8 between the line "F", tangent to the surface "G" of the groove, and the leg line "H", is substantially equal to the angle "E'" in Fig. 11 between the line "F'" tangent to the surface 60 "G'" of the groove and the leg line "H'". Thus, curling of the staple legs and reentrance of the staple points into the side material are always assured under all ordinary conditions of deflection of the staple legs.

65 The U-clinch produced by the clincher block herein has resulted in many practical advantages in the manufacture of wirebound boxes. It increases the holding power of the staple, eliminates projecting staple points, and permits the 70 use of thinner side material for the same strength in many types of commercial boxes. It also reduces the load on the stapling machine during the clinching operation and the consequent wear on the parts. This results from the 75

fact that it requires less force to curl the staple leg than it does to imbed the staple leg in the under side of the side material as has been the usual practice heretofore.

5 It will be understood that the invention is not to be limited to the specific embodiment shown for purposes of illustration as the inventive features may be variously embodied without departing from the invention.

10 It will also be understood further that all of the features of the invention need not be used conjointly as they may be used in various combinations as defined in the sub-joined claims.

15 This application is a continuation in part of my copending application Serial No. 671,635 filed May 18, 1933.

I claim:

20 1. Clincher means for box stapling machines comprising a metal block provided with two series of longitudinal grooves separated by a ridge whereby the legs of a staple driven through a box part resting upon the block will straddle the ridge and each leg will enter one of the grooves on its side of the ridge and will be curled in the direction of the groove, the bottom surface of the grooves being curved longitudinally of the groove at a suitable radius of curvature whereby the legs of the staple will be curved sufficiently to cause the staple point to reenter the box part at a point relatively remote from the point of emergence.

25 2. Clincher means for box stapling machines comprising a metal block provided with two series of parallel grooves separated by a ridge located at an angle to the direction of the grooves, the bottom surface of the grooves being curved downwardly from the ridge with a predetermined radius of curvature, whereby the legs of the staple driven through a box part resting upon the block will straddle the ridge and each leg will enter one of the grooves on its side of the ridge and will be curled in a direction away from the ridge with a radius of curvature sufficient to cause the staple point to reenter the box part at a point relatively remote from the point of emergence.

30 3. Clincher means for box stapling machines comprising a block provided with two series of parallel grooves separated by a ridge, the bottom surface of the grooves being curved downwardly from the ridge at a predetermined radius of curvature whereby the legs of the staple driven through a box part resting upon the block will straddle the ridge and each leg will enter one of the grooves on its side of the ridge and will be curled in a direction away from the ridge with a radius of curvature sufficient to cause the staple point to reenter the box part at a point relatively remote from the point of emergence.

35 4. Clincher means for box stapling machines comprising a metal block provided with two series of parallel grooves separated by a ridge located at an angle to the direction of the grooves, the bottom surface of the grooves being curved downwardly from the ridge with a predetermined radius of curvature, and the depth of the grooves being substantially equal to the diameter of a staple leg, whereby the legs of the staple driven through a box part resting upon the block will straddle the ridge and each

leg will enter one of the grooves on its side of the ridge and will be curled with a radius of curvature sufficient to cause the staple point to reenter the box part at a point relatively remote from the point of emergence while leaving that portion of the staple leg lying between said points beneath the under side of the box part.

5 5. Clincher means for box stapling machines comprising a metal block provided with two series of parallel grooves separated by a ridge, the bottom surface of the grooves being curved downwardly from the ridge with a predetermined radius of curvature, and the depth of the grooves being substantially equal to the diameter of a staple leg, whereby the legs of the staple driven through a box part resting upon the block will straddle the ridge and each leg will enter one of the grooves on its side of the ridge and will be curled with a radius of curvature sufficient to cause the staple point to reenter the box part at a point relatively remote from the point of emergence, while leaving that portion of the staple leg lying between said points beneath the under side of the box part.

10 6. A method of stapling a binding wire to a wooden box part which consists in driving the staple over the wire at an angle to the axis of the wire and at an angle to the grain of the wood, whereby the legs of the staple pass through the box part at spaced points across the grain of the wood, curling the legs of the staple which emerge from the under side of the box part away from each other and parallel to the axis of the wire and across the grain of the wood, and controlling the radius of the curls to cause the staple points to reenter the under side of the box part at points relatively remote from the points at which they emerged from the under side of the box part while maintaining substantially all of the intermediate portions of the staple legs below the under side of the box part, whereby the staple legs pierce the box part at four points spaced crosswise the grain of the wood while leaving the wood intermediate said points substantially free of impairment.

15 7. A method of stapling a binding wire to a sheet of box material which consists in driving the staple over the wire at an angle to the axis of the wire, curling the legs of the staple which emerge from the under side of the sheet in opposite directions parallel to the axis of the wire, and controlling the radius of the curls to cause the staple points to reenter the under side of the sheet at points relatively remote from the points at which they emerged from the under side of the sheet.

20 8. A method of stapling a binding wire to a box part which consists in driving the staple over the wire at an angle to the axis of the wire, curling the legs of the staple which emerge from the under side of the box part in opposite directions substantially parallel to the axis of the wire and controlling the radius of the curls to cause the staple points to reenter the under side of the box part at points relatively remote from the points at which they emerged from the under side of the box part.
